UNITED STATES PATENT OFFICE.

HERBERT C. CHASE, OF STONINGTON, CONNECTICUT, ASSIGNEE TO ATWOOD MACHINE COMPANY, OF STONINGTON, CONNECTICUT, A CORPORATION OF NEW JERSEY.

REEL MILL.

Application filed October 6, 1922. Serial No. 592,906.

In reel mills as ordinarily built, the reel shafts have been provided with permanently fixed bearing supports, making it quite difficult to take the reels out of the gear 5 while the machine was running.

The object of this invention is to provide novel means for disconnecting the reels from their driving mechanism to permit the removal of the reels, which means more 10 specifically comprises a movable bearing support for one end of each reel shaft, whereby the reel gear may be disconnected from its driving gear, means being provided for holding the bearing support in its different positions.

A practical embodiment of my invention is represented in the accompanying drawings, in which—

Fig. 1 represents a detail end view of a 20 reel mill with my improvement applied thereto.

Fig. 2 represents a detail front view.

Fig. 3 represents a section taken in the 25 plane of the line III—III of Fig. 2 with the parts in the positions they assume when the reel gears have been disconnected from their driving gears.

Fig. 4 represents a detail plan view of 30 one of the movable bearing supports.

Fig. 5 represents a detail side view of the same.

Fig. 6 represents a detail vertical section 35 on an enlarged scale, showing the means for vertically adjusting the hinged connection between the movable bearing support and the end frame.

The end frame of the wheel mill is denoted by 1. The upper reel shaft is denoted by 2 and its end adjacent to the frame 40 1 is suitably mounted in a vertically movable support 3, hinged to the end frame. In the present instance the inner end of the movable bearing support is pivoted on a stud 4, carried by a bracket 5 which is vertically adjustable along the end frame 1 by 45 providing the bracket with screw studs 6 which pass through vertically elongated slots 7 in the end frame. The outer end of this upper movable bearing support is provided with a handle 8 to which is pivoted a latch 9, the nose 10 of which is arranged to be brought into engagement with either 50 one of two notches 11, 12, in the end frame.

The end of the upper reel shaft 2 opposite to the end that is supported in the mov-

able bearing support 3 is suitably mounted in a permanently fixed bearing support (not shown herein).

This upper reel shaft 2 is provided with a gear 13 which meshes with the gear 14 of the driving mechanism when the bearing support 3 is lowered to bring the nose 10 of the latch 9 into the notch 12, in the end frame.

The bearing support 3 may be swung upwardly to disconnect the reel gear 13 from its driving gear 14 and the parts may be supported in this position by causing the nose 10 of the latch 9 to enter the notch 11 in the end frame.

The end of the lower reel shaft 15 adjacent to the end frame 1 is mounted in the bearing support 16, which bearing support is quite similar to the bearing support 3 already described. This bearing support 16 is pivoted on a stud 17, carried by a vertically adjustable bracket 18. The outer end of this bearing support 16 is provided with a handle 19 to which is pivoted a latch 20, the nose 21 of which is arranged to enter one of two notches 22, 23 in the end frame 1. The lower reel shaft 15 is provided with a gear 24 which meshes with the gear 25 of the driving mechanism.

To disconnect the gear 24 from its driving gear 25, the latch 20 is manipulated to release the nose 21 from the notch 22 and the bearing support 16 is lowered and the nose 21 of the latch 20 is brought into engagement with the notch 23 to hold the 90 parts in this position.

From the above description it will be seen that I have provided a very simple means for disconnecting the reel shafts from their driving mechanism while the 95 machine is in operation, thus facilitating the removal of the reels from the machine.

It is evident that various changes may be resorted to in the construction, form and arrangement of the several parts without departing from the spirit and scope of my invention, hence I do not wish to be limited to the particular embodiment herein shown and described, but what I claim is:—

1. An end frame, a reel shaft, a reel gear 105 mounted thereon, a driving gear meshing with the reel gear, and a support provided with an open bearing for receiving the end of the reel shaft adjacent the reel gear, said support being carried by the end frame and 110

- movable to disconnect the reel gear from its driving gear.
2. An end frame, a reel shaft, a reel gear mounted thereon, a driving gear meshing with the reel gear, a support provided with an open bearing for receiving the end of the reel shaft adjacent the reel gear, said support being carried by the end frame and movable to disconnect the reel gear from its driving gear, and means arranged to coact with the movable support and end frame for holding the support in different positions.
3. An end frame, a reel shaft, a reel gear mounted thereon, a driving gear meshing with the reel gear, and a vertically swinging support provided with an open bearing for receiving the end of the reel shaft adjacent the reel gear, said support being carried by the end frame and movable to disconnect the reel gear from its driving gear.
4. An end frame, a reel shaft, a reel gear mounted thereon, a driving gear meshing with the reel gear, a vertically swinging support provided with an open bearing for receiving the end of the reel shaft adjacent the reel gear, said support being carried by the end frame and movable to disconnect the reel gear from its driving gear, and means arranged to coact with the movable support and end frame for holding the support in different positions.
5. An end frame, a reel shaft, a reel gear mounted thereon, a driving gear meshing with the reel gear, and a horizontally disposed support provided with an open bearing for receiving the end of the reel shaft adjacent the reel gear, said support having its inner end pivoted to the end frame and movable arcuately in a vertical direction to disconnect the reel gear from its driving gear.
6. An end frame, a reel shaft, a reel gear mounted thereon, a driving gear meshing with the reel gear, a horizontally disposed support provided with an open bearing for receiving the end of the reel shaft adjacent the reel gear, said support having its inner end pivoted to the end frame and movable arcuately in a vertical direction to disconnect the reel gear from its driving gear, and means arranged to coact with the movable support and end frame for holding the support in different positions.

7. An end frame, a pair of reels arranged substantially in vertical alinement, their driving mechanism, and means carried by said end frame and operable in opposite directions to disconnect the reels from their driving mechanism.
8. An end frame, a pair of reels arranged substantially in vertical alinement, their gears, driving gears meshing with the reel gears, and means carried by said end frame and operable in opposite directions to disconnect the reel gears from their driving gears.
9. An end frame, a pair of reel shafts, reel gears, driving gears meshing with the reel gears, and bearing supports for the ends of the reel shafts adjacent the reel gears, said supports being carried by said end frame and movable in opposite directions to disconnect the reel gears from their driving gears.
10. An end frame, a pair of reel shafts, reel gears, driving gears meshing with the reel gears, bearing supports for the ends of the reel shafts adjacent the reel gears, said supports being carried by said end frame and movable in opposite directions to disconnect the reel gears from their driving gears, and means for holding the movable supports in their different positions.
11. An end frame, upper and lower reel shafts, reel gears, driving gears meshing with the reel gears, and supports for corresponding ends of the reel shafts hinged to the end frame, the upper support being movable upwardly and the lower support being movable downwardly, to disconnect the reel gears from their driving gears.
12. An end frame, upper and lower reel shafts, reel gears, driving gears meshing with the reel gears, supports for corresponding ends of the reel shafts hinged to the end frame, the upper support being movable upwardly and the lower support being movable downwardly, to disconnect the reel gears from their driving gears, and latch connection between the movable supports and end frame for holding the movable supports in their different positions.

In testimony, that I claim the foregoing as my invention, I have signed my name this 4th day of October, 1922.

HERBERT C. CHASE.
